UNITED STATES PATENT OFFICE

JAMES M. HOWE, OF CLEVELAND HEIGHTS, OHIO, ASSIGNOR TO EATON MANUFACTURING COMPANY, OF CLEVELAND, OHIO, A CORPORATION OF OHIO

AUTOMOBILE HEATER

Application filed August 20, 1930. Serial No. 476,555.

This invention relates to automobile heaters, and more particularly to devices of this character associated with the exhaust pipe from the motor, in order to utilize the heat of the exhaust gases for heating air for the passenger compartment of a motor vehicle.

It is an object of the invention to simplify and improve the construction and operation of devices of this character to render them inexpensive to manufacture and otherwise well adapted for the purposes set forth.

Another object of the invention is to improve the heat radiating and air baffling provisions of devices of this character.

A further object is to provide a readily removable cover for the heater to facilitate cleaning the fins.

Other objects and features of novelty will be apparent as the following description proceeds, reference being had to the accompanying drawing, in which

Figure 1 is a view partly in elevation and partly in longitudinal section through an automobile heater according to the preferred embodiment of the present invention;

Fig. 2 is a transverse section taken along the line 2-2 of Fig. 1;

Fig. 3 is a development of the outer ends of the heat radiating fins;

Fig. 4 is an enlarged detail section showing the mounting of the heat radiating fins on the central tube;

Fig. 5 is a detail perspective view of one of the annular members forming the heat radiating fins; and

Fig. 6 is a detail section showing a modified construction for holding the fins on the tube.

Referring more particularly to the drawing, the heater comprises a central tube 10, one end of which is slotted as at 35 for connection to the motor exhaust pipe, as by means of a clamp 12. The other end of the tube 10 slotted as at 36 is provided with a similar clamp 13, for clamping over the remaining portion of the exhaust pipe. The tube 10 must be imperforate, but the same may be of welded tubing or other construc-

tion which is adequately impervious to prevent escape of exhaust gases therethrough.

Surrounding the tube 10 is a casing 14, preferably constructed of sheet metal, and defining with the tube 10 an annular air chamber 15, provided adjacent one end with a fresh air inlet 16, and adjacent the other end with an outlet 17 for the heated air. The outlet 17 may be connected in any desired manner to the passenger compartment 60 of the automobile.

The casing 14 comprises a pair of annular headers 30 which are stamped into channel cross-section, forming inner flanges 31 which are welded to tube 10, and outer flanges 32, around which is wrapped a sheet metal cover 33, containing the inlet 16 and the outlet 17. The edges of the cover are brought together in a fold or crimp joint 38, and the cover is secured to the flanges 32 by 70 clamps 34.

Mounted in the chamber 15 between the inlet 16 and the outlet 17 are a plurality of fins 18. These fins are preferably arranged in staggered annular series extending about 75 the tube 10. Each fin 18 has a central aperture 19, and a vane 20 which is bent out of the plane of the main portion of the fin. The fins 18 are preferably connected by an annular flange 21 extending around the tube 80 10.

In the form shown, the fins are constructed by stamping out annular rings from sheet metal, such as shown in Fig. 5, in which the fins 18 are integral with the flange 21 and 85 radiate therefrom, portions of the metal being cut away between the fins and the vanes 20 being bent down from the edges thereof.

As shown in Fig. 4, the annular flange 21 is tapered, slotted as at 22, and is provided 90 with a shoulder 23. This arrangement permits the flanges 21 to be fitted over the tube 10 in a sort of nested relation, in that the flange 21 of one series will project under the shoulder 23 of the next series, and longitudinal pressure upon the nested members will cause the shoulders 23 to clamp the flanges 21 tightly against the tube 10, which is preferably coated with an iron cement 37, such as sal ammoniac and iron fillings, before 100

assembly, to insure a good joint between the flanges 21 and the tube 10.

The annular members may be assembled by means of bolts 24, which are passed alternately through the apertures of the staggered fins, and alternately through the slots between the fins of the intermediate discs. After assembly upon the tube 10, these bolts may be tightened to cause the clamping of the flanges 21. The vanes 20 of the fins 18 are preferably arranged as shown in Fig. 3, so as to define substantially helical channels extending through the air chamber 15.

The fins 18 arranged as described above, are very efficient for heat transfer purposes. The tight joint between the flanges 21 and the tube 10 insures rapid radiation through the fins 18, and the passage of the air to be heated through the central apertures of the fins insures heat transfer from the fins to the air being heated. At the same time the helical channels provided by the vanes 20 insure circumferential as well as longitudinal travel of the air through the chamber 15, and thus prevent any pocketing or dead spots in the circulation of the air.

To insure corresponding heat transfer from the exhaust gases to the tube 10, a helical baffle 25 is fitted in the tube 10, and preferably comprises a flat strip of sheet metal, given a half turn or more to bring it into the desired helical form, the ends of the strip being secured as at 26 to the tube 10 by spot welding or other suitable connection.

The manufacture of the heater may be varied by assembling the annular members on the tube under pressure, and welding the flanges to the tube at each end while under pressure. Thus the bolts 24 may be omitted, other means being employed for alignment during assembly. In lieu of welding, beads 39 may be formed in the tube after assembly under pressure, to hold the members in position, as shown in Fig. 6.

The fins have a further utility in retaining foreign particles carried by the fresh air, thus cleaning the air to be heated. The accumulated particles may be removed from the fins by merely removing the cover 14, which is preferably formed of two halves made by the same dies, the crimp joints 38 permitting ready removal.

While one embodiment of the invention has been illustrated and described in such detail as to enable any one skilled in the art to practice the invention, nevertheless it is to be understood that the invention is not to be limited to any of the details disclosed, other than as necessitated by the development of the prior art, but, instead, it is to be understood that the invention embraces such embodiments of the broad idea as fall within the scope of the appended claims, it being obvious that changes may be resorted to with re-

spect to the disclosed invention without departing from the spirit of the invention.

Having thus described my invention what I claim is:

1. In an automobile heater, in combination, a central tube adapted to receive the motor exhaust gases, a casing surrounding said tube and forming therewith an annular air chamber, said chamber having an inlet and an outlet, and a plurality of staggered radial fins therebetween, said fins having central apertures, and retaining means extending longitudinally of said chamber and passing alternately through said apertures and between said fins. 70

2. In an automobile heater, in combination, a central tube adapted to receive the motor exhaust gases, channel shaped annular headers having their inner flanges secured to said tube, a series of annularly spaced radial fins mounted on said tube between said headers, means for securing said fins on said tube, and a cylindrical cover secured to the outer flanges of said headers and having an air inlet and an air outlet therein. 75

3. In an automobile heater, in combination, a central tube adapted to receive the motor exhaust gases, a casing surrounding said tube and forming therewith an annular air chamber, said chamber having an inlet and an outlet, and a plurality of annular sheet metal members therebetween having central annular flanges interfitting and secured to said tube, said annular members being radially slotted to form heat radiating fins, said fins having central apertures, and flanges on one side of said fins, said annular members being staggered, and bolts passing alternately through the slots and apertures to hold said flanges in position to form helical channels in said annular air chamber. 95

4. In an automobile heater, in combination, a central tube adapted to receive the motor exhaust gases, a casing surrounding said tube and forming therewith an annular air chamber, said chamber having an inlet and an outlet, and a plurality of longitudinally spaced radial fins therebetween, said fins having a tapered connecting flange extending around said tube, the flange associated with certain of said fins interfitting with the flange associated with the longitudinally adjacent fins and secured to said tube by an iron cement. 110

5. In an automobile heater, in combination, a central tube adapted to receive the motor exhaust gases, a casing surrounding said tube and forming therewith an annular air chamber, said chamber having an inlet and an outlet, and a plurality of longitudinally spaced radial fins therebetween, said fins having a tapered connecting flange extending around said tube, the flange associated with certain of said fins interfitting with the flange associated with the longi- 125

130

tudinally adjacent fins, said flanges being assembled under pressure, and said tube having beads formed therein engaging the end flanges for holding the flanges therebetween on said tube.

6. In an automobile heater, in combination, a central tube adapted to receive the motor exhaust gases, annular headers secured to said tube, a series of spaced radial fins 10 mounted on said tube between said headers, and a removable cylindrical cover, having interfitting edge portions, said interfitting portions including a folded portion adjacent one of said edges and clamps for removably 15 securing said sections to said headers.

In testimony whereof, I hereunto affix my signature.

JAMES M. HOWE.
